(57) **CLAIM**

The ornamental design for a projection display, as shown and described.

DESCRIPTION

FIG. 1 is a perspective view of a projection display showing my new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view thereof;

FIG. 9 is a perspective view thereof accommodating a remote;

FIG. 10 is a partially exploded view thereof; and,

FIG. 11 is a partially exploded bottom plan view thereof.

The broken lines in the drawings depict portions of the projection display that form no part of the claimed design.
